UNITED STATES PATENT OFFICE.

WALTER P. ALLEN, OF JERSEY CITY HEIGHTS, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 4, 1924. Serial No. 729,919.

My invention relates to railway traffic controlling apparatus of the type wherein traffic governing means located on the car or train is controlled by energy received from the trackway and the supply of energy from the trackway to the train depends upon traffic conditions in advance of the train. The present invention is particularly well adapted for apparatus of this character in which the governing means on the train requires the constant supply of energy from the trackway to prevent an automatic application of the brakes, although it is not limited to this specific adaptation.

5

10

15

In connection with systems of this nature, it has been proposed to provide apparatus on the train under the control of the engineer for restraining the automatic application of the brakes if the engineer takes suitable action at the time of cessation of the supply of energy from the trackway, and it has also been proposed to provide auxiliary means located at intervals in the trackway for supplying energy to the train after the cessation of the normal supply of energy, thereby causing an automatic application of the brakes when the auxiliary supply of energy ceases unless the engineer prevents such application by again operating the suppressing apparatus already referred to. The features just mentioned are disclosed and claimed in United States Letters Patent No. 1,492,357, granted to R. A. McCann on May 6, 1924.

20

25

30

35

One feature of my invention is the provision, in a system of the type just referred to, of means for checking the auxiliary means located in the trackway for supplying energy to the train.

40

45

I will describe one form of apparatus embodying my invention and will then point out the novel features thereof in claims.

The accompanying drawing is a diagrammatic view showing one form of apparatus embodying my invention.

50

55

Referring to the drawing, the reference characters 10 and 11 designate the track rails of a railway along which traffic normally moves in the direction indicated by the arrow, and which rails are divided by insulated joints 12 into a plurality of blocks A—B, B—C, etc. Located adjacent

the entrance end of each block is a roadside signal designated by the reference character S, with an exponent corresponding to the location. Each of these signals, as here shown, is of the semaphore type adapted to indicate "stop," "caution" or "proceed". The apparatus for controlling these signals will be referred to hereinafter, it being sufficient to say at the present time that each signal indicates proceed when the corresponding block and the block next in advance are unoccupied, caution when the corresponding block is unoccupied and the block next in advance is occupied, and stop when the corresponding block is occupied.

60

65

70

Each block is provided with means for connecting a source of alternating train controlling current across the track rails at the exit end of the block. As here shown, this means comprises a transformer which is designated by the reference character F, 75 with an exponent corresponding to the location. The primary winding 6 of each transformer F is connected with a transmission line D^T, which line is constantly supplied with alternating train controlling 80 current by a suitable generator E^T. The secondary 7 of each transformer F is connected across the rails through a contact designated by the reference character H, 85 with an exponent corresponding to the location. This contact is controlled by the adjacent signal S in such manner that the contact is closed when the signal indicates proceed or caution, but open when the signal indicates stop. It follows that alternating 90 train controlling current is connected across the rails of each block when the signal for the block next in advance indicates caution or proceed, that is, when the said block next in advance is unoccupied, but that this 95 source of current is disconnected from the rails of the block when the block next in advance is occupied.

Located adjacent the exit end of each block is an auxiliary means for supplying train controlling energy to trains traveling along the trackway. This means, as here shown, is a trackway loop designated by the reference character L, with an exponent corresponding to the location, which loop is 100 constantly connected with the secondary 8 of the adjacent transformer F through the winding of a checking relay designated by 105

the reference character K, with an exponent corresponding to the location. The function of the relays K will be pointed out hereinafter.

5 The trackway apparatus illustrated in the accompanying drawing is intended for co-operation with train carried apparatus in such manner that when the train is supplied with train governing energy from the track-
10 way an automatic application of the brakes is prevented, but that when the supply of train governing energy from the trackway ceases, the brakes will be applied automatically unless the engineer takes suitable action
15 to prevent such application. The train carried apparatus is omitted from the drawing for the reason that it forms no part of my present invention. One form of train-
20 carried apparatus which will operate in the manner specified, is illustrated and described in the McCann Patent No. 1,492,719, referred to above.

The operation of the apparatus thus far described, is as follows:

25 As shown in the drawing, a train V occupies the block immediately to the left of point A, so that signal S^A indicates stop, and the supply of train controlling energy to the track rails of block A—B is discontinued. Signal S^B indicates caution, and signal S^C indicates proceed, so that train controlling energy is supplied to the rails of block B—C and the block to the right of point C. If now a following train moving
30 in the direction indicated by the arrow enters block B—C, it will receive a proceed indication throughout this block and so may pass through the entire block without incurring an automatic application of the brakes.
35 When such following train enters block A—B, however, the supply of train controlling energy from the track rails to the train will be discontinued and an automatic application of the brakes will be incurred unless the engineer takes suitable action to restrain such application. When the train passes over the trackway loop L^A, the train-
40 carried apparatus will again be energized, and as soon as the train leaves this loop the train-carried apparatus will again become deenergized, thereby again causing an automatic application of the brakes unless the engineer again takes suitable action to restrain such application.
45

50 55 Each block is provided with a track circuit comprising a transformer designated by the reference character T, with an exponent corresponding to the location, and a track relay designated by the reference character R, with an exponent corresponding to the location. As here shown, each transformer T is located adjacent the entrance end of the block and the primary of each of these transformers is connected with a transmission line D^s constantly supplied with alternating

track circuit current by a generator E^s. Each track relay R is located adjacent the exit end of the block and comprises a track winding 2 connected across the track rails and a local winding 3 supplied with current 70 from the transmission line D^s. Each track relay further comprises a rotor 4 operating a contact 5 in such manner that the contact is closed when the block is unoccupied, and open when the block is occupied. 75

Each signal S is provided with a circuit which passes from the upper wire of the transmission line D^s, through contact 5 of the track relay R for the corresponding block, contact 9 of the checking relay K for the corresponding block, and the operating mechanism of the signal to the lower wire of the transmission line D^s. It is understood that each signal will be further provided with additional controlling apparatus, 85 but for purposes of the present invention it is sufficient to say that each signal will indicate stop, unless the circuit just traced is closed at both contacts 5 and 9.

Assuming now that the auxiliary loop J^A 90 becomes broken, or that the supply of current to this loop is interrupted for any reason whatsoever, it will be apparent that a train passing over this loop would not receive the second automatic brake application referred to above, and, consequently, such train might enter the occupied block to the left of point A without being properly under control. If this loop is broken, however, or if for any other reason the supply of train governing energy to the loop is interrupted, the checking relay R^A will be open, so that signal S^B will be at stop. Contact H^B will then be open, so that the supply of train governing energy to the rails of block B—C will be interrupted, whereupon a following train will receive an automatic brake application at the point C and a second automatic brake application at the loop L^B. The relay K^A thus functions as an automatic check on the integrity of the loop J^A 100 and the circuit supplying energy to this loop. 105

The foregoing explanation of the function of relay K^A applies to each of the remaining relays K.

I do not in this application make any claim for the combination of a track circuit comprising a source of energy at the entrance end and a track relay at the exit end, together with means for supplying train governing energy to the track rails at the exit end of the block, such combination being the invention of Robert M. Gilson, and disclosed and claimed by him in an application filed on the nineteenth day of August, 1924, Serial No. 732,927. 115 120 125

Although I have herein shown and described only one form of apparatus embodying my invention, it is understood that vari- 130 135

ous changes and modifications may be made therein within the scope of the appended claims without departing from the spirit and scope of my invention.

Having thus described my invention, what I claim is:

1. Railway traffic controlling apparatus comprising a series of main trackway circuits for supplying controlling energy to trains continuously under safe traffic conditions but not under unsafe traffic conditions, a plurality of auxiliary trackway circuits for supplying controlling energy to trains at spaced intervals, and means included in each auxiliary circuit for governing a main circuit.
2. Railway traffic controlling apparatus comprising a series of main trackway circuits for supplying controlling energy to trains continuously under safe traffic conditions but not under unsafe traffic conditions, a plurality of auxiliary trackway circuits for supplying controlling energy to trains at spaced intervals, a relay included in each auxiliary circuit, and means for controlling a main circuit by each relay.

3. Railway traffic controlling apparatus comprising a trackway divided into blocks, a main circuit for each block for supplying energy to trains throughout the block under safe traffic conditions but not under unsafe traffic conditions, an auxiliary circuit for each block for supplying energy to trains through only a portion of the block, and means for governing the main circuit for each block by the auxiliary circuit for a block in advance.

4. Railway traffic controlling apparatus comprising a trackway divided into blocks, a signal for each block, a main circuit for each block governed by the signal for the block next in advance for supplying energy to trains throughout the block under safe traffic conditions in advance but not under unsafe traffic conditions in advance, an auxiliary train controlling circuit for each block for supplying energy to trains through only a portion of the block, and means for controlling each signal by the auxiliary circuit for the associated block.

5. Railway traffic controlling apparatus comprising a trackway divided into blocks, a main train controlling circuit for each block including the track rails of the block for supplying energy to trains throughout the block under safe traffic conditions in advance but not under unsafe traffic conditions in advance, an auxiliary train controlling circuit for each block including short conductors parallel with the rails of the block for supplying energy to trains through only a portion of the block, and means for governing the main circuit for each block by

the auxiliary circuit for a block in advance.

6. Railway traffic controlling apparatus comprising a trackway divided into blocks, a main train controlling circuit for each block for supplying energy to trains throughout the block under safe traffic conditions in advance but not under unsafe traffic conditions in advance, an auxiliary train controlling circuit for each block for supplying energy to trains through only a small portion of the block, and means for governing the main circuit for each block by the auxiliary circuit for a block in advance.

7. Railway traffic controlling apparatus comprising a trackway divided into blocks, a main train controlling circuit for each block for supplying energy to trains throughout the block under safe traffic conditions in advance but not under unsafe traffic conditions in advance, an auxiliary train controlling circuit for each block for supplying energy to trains through only a small portion of the block, a signal for each block controlled in part by the auxiliary circuit for the associated block, and means for controlling the main circuit for each block by the signal for the block next in advance.

8. Railway traffic controlling apparatus comprising a trackway divided into blocks, a signal for each block, a main trackway circuit for each block controlled by the signal for a block in advance for supplying energy to trains throughout the block under safe traffic conditions in advance but not under unsafe traffic conditions in advance, an auxiliary trackway circuit for each block for supplying energy to trains through only a portion of the block, and a relay included in each auxiliary circuit for controlling the signal for the associated block.

9. Railway traffic controlling apparatus comprising a series of main trackway circuits for continuously supplying energy to trains by induction under safe traffic conditions but not under unsafe traffic conditions, a series of auxiliary trackway circuits for supplying energy to trains inductively at spaced intervals, and means included in each auxiliary circuit for governing a main circuit in the rear.

10. Railway traffic controlling apparatus comprising means located in the trackway for supplying train controlling energy to trains continuously under safe traffic conditions but not under unsafe traffic conditions, auxiliary means located in the trackway for supplying train controlling energy to trains at spaced intervals, and means for controlling said first means by said second means.

In testimony whereof I affix my signature.

WALTER P. ALLEN.
